UNITED STATES PATENT OFFICE.

BENJAMIN H. ERWIN, OF MISHAWAKA, INDIANA.

TRUNK ATTACHMENT.

Application filed June 22, 1925. Serial No. 38,835.

The invention relates to attachments for wardrobe trunks and has for its object to provide a shoe box attachment for a wardrobe trunk, which shoe box attachment is disposed within the lower end of the main body of the trunk adjacent its open side, and is suspended on brackets, which brackets form means for supporting the box in a vertical or a horizontal plane, and are provided with means for preventing swinging when in a vertical plane.

A further object is to provide the opposite sides of the box with upwardly extending plates, which plates are provided with spaced hooks adjacent their upper ends, the upper hooks forming pivotal hooks for the plates when the shoe box is moved to a horizontal or vertical plane, and the lower hooks cooperate with apertured arms carried by plates secured to the inner sides of the trunk and hold the plates and shoe box against swinging when in a vertical plane, but allow the shoe box and plates to be raised vertically for positioning the upper hooks of the plates above the pivot pins of trunk carried plates when it is desired to entirely detach the shoe box from the trunk.

A further object is to provide the trunk carried plates with flanges above the pivot pins with which the box carried plates engage in connection with the pivot pins when in a horizontal position for holding the shoe box in a horizontal position.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:—

Figure 1 is a perspective view of the lower portion of the body of a wardrobe trunk, showing the shoe box applied thereto.

Figure 2 is a view similar to Figure 1, showing the shoe box supported in a horizontal position.

Figure 3 is a perspective view of the shoe box.

Figure 4 is an enlarged perspective view of one of the supporting brackets for the shoe box.

Referring to the drawing, the numeral 1 designates the body of a conventional form

of wardrobe trunk and 2 the shoe box which is provided with a cover 3, hingedly connected to the shoe box at 4, and which cover is provided with a handle member 5 adapted to be grasped by the operator during the manipulation of the device. Cover 3 is provided with a catch for holding the same closed, which catch may be of any conventional form.

In wardrobe trunks the storage of shoes presents a problem, as it is necessary to place the shoes with the clothing or in drawers with clothing, and during transportation the shoes soil or injure the clothing, and to obviate this difficulty the shoe box is primarily designed. Secured to opposite sides 7 of the trunk body 1 by means of screws 8 which pass through the flanges 9 are inwardly offset plates 10, in parallel relation to the sides 7. The plates 10 are connected to the flanges 9 by means of horizontally disposed flanges 11. The lower end of the plates 10 terminate in inwardly extending arms 12, which are provided with apertures 13, and which arms 12 terminate in vertically disposed ears 14 having apertures 15 for the reception of screws for securing the ears to the sides 7, therefore it will be seen that the plates 10 are rigidly attached to the sides 7 of the body of the trunk in spaced relation thereto. Secured at 16 to opposite sides of the shoe box 2 are plates 17, which plates extend upwardly and terminate in arms 18, which extend between the plates 10 and the sides 7 of the trunk body. Arms 18 are provided with spaced hooks 19 and 20, which cooperate with the horizontally disposed pins 21 carried by the plates 10 and the apertures 13 in the arms 12 of the plates. When the shoe box 2 is in a vertical position as shown in Figure 1, the noses 22 of the hooks 20 are disposed in the apertures 13, and the pins 21 are in the recesses 23 of the hooks 19, therefore it will be seen that the shoe box will be rigidly held in a vertical plane and will not swing inwardly and outwardly, and at the same time the shoe box 2 is supported in a vertical position adjacent the open end of the body 1 of the trunk. When it is desired to have access to the shoe box, the operator grasps the handle member 5 and raises the shoe box 2 slightly until the noses 22 of the hooks 20 are out of the apertures 13, then the free end of the shoe box is swung upwardly, which action will position the arms

- 18 where a slight inward movement of the box as a whole will position the outer ends of the arms where they will engage the under side of the flanges 11 and rest upon the 5 upper sides of the pins 21, and will support the shoe box in a horizontal plane. If it is desired to entirely remove the box, instead of swinging the same upwardly to a horizontal position after it has been raised, the 10 operator pulls outwardly on the box, and as the pins 21 are out of the recesses 23 of the hook 19, the box may be easily removed from the trunk, thereby allowing the entire chamber of the trunk to be utilized for 15 hanging clothes in the usual manner, however in transit the box is in place in the trunk. When moving the box from a horizontal to a vertical position, the operator pulls outwardly on the box until the hooks 20 engage the pins 21, which allows the same to swing downwardly until the bevelled edges 24 of the hooks 20 engage the edges of the flanges 12, which bevelled edges will, under complete inward movement 25 of the lower free end of the box, move the arms 18 and consequently the box upwardly incident to the camming action of said bevelled edges on the edges of said flanges, and the latching noses 22 engage 30 the apertures 13 and as the recesses 23 of the hooks 19 are of greater depth than the length of the noses 22, it is obvious that inward swinging of the free end of the box during this action will be permitted and 35 disengagement of the hooks 19 in relation to the pins 21 will be prevented.

From the above it will be seen that a shoe box is provided for a wardrobe trunk, which shoe box is simple in construction, is suspended in a position where it will not interfere with the hanging of clothing in the trunk, and constructed in a manner whereby it may be suspended in a vertical position against swinging in a trunk, supported in 45 a horizontal position or entirely removed from the trunk.

The invention having been set forth what is claimed as new and useful is:—

1. The combination with a trunk body, of 50 a shoe box hinged adjacent its top side, oppositely disposed bracket members carried by said body, and means carried by the shoe box adjacent its hinging point cooperating with the bracket members, and adapted up- 55 on a relative shifting and positioning thereof with relation to said bracket members for hingedly and detachably mounting and for supporting said shoe box in a vertical or a horizontal position.
2. The combination with a trunk body, of 60 a shoe box, bracket members carried by said trunk body, arms carried by and extending beyond the upper end of the shoe box cooperating with the bracket members 65 and adapted upon a relative shifting and

positioning thereof with relation to said bracket members for hingedly and detachably mounting and for supporting said shoe box in a vertical or a horizontal position, and having further means for locking the 70 shoe box in a vertical position.

3. The combination with a trunk body, of a shoe box, means for pivotally and detachably connecting the shoe box to the trunk body, said means including arms carried by the shoe box, spaced hook members carried by each of said arms, and brackets carried by the trunk body including bearing and latching members adapted to cooperate with said arms and hook members upon a 80 relative shifting and positioning thereof to support said shoe box in a vertical or a horizontal position and to lock the shoe box against pivotal movement, all of said arms and brackets being disposed adjacent the 85 hinged side of the box.

4. The combination with a shoe box disposed between spaced walls of a trunk, supporting means for said shoe box, said means comprising inwardly offset plates carried by the spaced walls, a flange carried by the upper ends of said plates, pins carried by the inner sides of said plates, arms carried by the shoe box, said arms being disposed between the pins and the plate flanges when 90 the box is in a horizontal position, apertured members carried by the lower ends of the plates, hooks carried by the outer ends of the arms and cooperating with the pins for supporting the box in a vertical position 95 and limiting the outward movement of the box when in a horizontal position, and hooks carried by the arms and cooperating with the apertures of the apertured members for holding the box against outward movement 100 when in a vertical position.

5. The combination with a shoe box disposed between spaced walls of a trunk, of supporting brackets for said box, said brackets comprising arms carried by the box, inwardly offset plates carried by the spaced walls, spaced hooks carried by the arms, spaced stops carried by the plates, one of said stops being disposed between the spaced 110 hooks of the arms when in horizontal position, and apertured members carried by the plates and with which one of the hooks of the arms cooperate for holding the box against swinging when in a vertical position.

6. The combination with a shoe box disposed between spaced walls of a trunk having arms extending therefrom, of supporting brackets for said shoe box, said brackets comprising spaced stops carried by the walls, spaced hooks carried by the arms on the box, one of said stops being disposed between the hooks, said stops supporting the arms in a horizontal position, one of the hooks of the arms cooperating with one of the stops for supporting the arms and box in a vertical 125 130

position, apertured members carried by the walls, the other hooks of the arms cooperating with the apertured members whereby swinging of the box will be prevented when

5 in a vertical position.

7. The combination with a receptacle hingedly mounted between spaced walls of a trunk, said receptacle being provided with arms having hooks, said hooks cooperating with pins forming supporting and hinging means for the receptacle, of stops above the pins and cooperating with the arms and the pins for holding the arms in a horizontal position, hooks spaced from the first mentioned hooks, apertured members carried by the trunk sides, said last named hooks cooperating with the apertured members and forming means whereby the arms and receptacle will be prevented from swinging

20 when in a vertical position.

8. A trunk receptacle hinge comprising an arm secured to a receptacle, a plate secured to a wall of the trunk, a pin carried by said plate, a flange carried by the plate above

25 the pin, an apertured member carried by the plate below the pin, spaced hooks carried by

the arm and between which the pin is disposed, said pin and flange forming means for maintaining the arm in a horizontal position, one of said hooks cooperating with the pin for supporting the arm in a vertical position, the other hook cooperating with the apertured member for holding said arm against swinging when in a vertical position.

9. A trunk receptacle hinge comprising an arm, a plate, spaced stops carried by said plate and between which the arm is disposed when in a horizontal position, and held in a horizontal position, an apertured member carried by the plate, one of said stops being disposed between spaced hooks, the outer hook having its recess deeper than the recess of the inner hook, said inner hook cooperating with the apertured member for latching the arm in a vertical position, said arm when in a vertical position being vertically movable to a position where its outer hook may move outwardly from between the spaced stops.

In testimony whereof I affix my signature.
BENJAMIN H. ERWIN.
